JOSHUA W. GASKILL AND JAMES CHRISTIE, OF PHILLIPSBURG, NEW JERSEY.

Letters Patent No. 97,901, dated December 14, 1869.

IMPROVEMENT IN THE MANUFACTURE OF NUTS.

The Schedule referred to in these Letters Patent and making part of the same.

We, JOSHUA W. GASKILL and JAMES CHRISTIE, of Phillipsburg, county of Warren, and State of New Jersey, have invented an Improvement in the Manufacture of Nut-Blanks, of which the following is a specification.

Nature and Object of the Invention.

Our invention consists in forming nut-blanks, partly by pressing and indenting the same when the metal is hot, and completing them by punching when the metal is cold, or nearly so, as fully explained hereafter.

The object of our invention is to produce a nut, which shall possess all the combined advantages of a forged and a cold-punched nut, and none of the disadvantages of either.

Description of the Accompanying Drawing.

Figure 1 is a longitudinal section of a machine, which may be used in carrying out a part of our invention;

Figure 2, a plan view of the same;

Figures 3, 4, and 5, enlarged views, in different positions, of a portion of fig. 1, illustrating the preparatory process of forming the nut-blanks;

Figure 6, an enlarged view of a nut-blank, showing the method of completing our process; and

Figure 7, a view of a finished blank, ready to be tapped.

General Description.

In the manufacture of nuts, the blanks are usually cut from a heated bar, and pressed up and punched between dies while hot, or they are cut out from cold bars, and punched simultaneously with the cutting.

The hot-pressed blanks have the advantage of being thoroughly pressed, and of being perfectly formed, externally, between the dies; but in punching the metal, a hard, brittle skin or scale adheres to the sides of the opening, and this scale, in tapping the blanks, interferes with the formation of a perfect thread, and speedily destroys the tap.

The cold-punched blanks, on the contrary, being free from this scale, can be tapped with the greatest facility, but they lack the external finish and solidity of the hot-pressed nut.

By our invention, which we will now proceed to describe, all the advantages of both of the old processes can be secured, and their disadvantages obviated.

The machine illustrated in the drawing, relates to the hot-pressing portion of the process, and is constructed as follows:

A represents the bed-plate of the machine, to which are secured the bearings *a a* of the cranked driving

shaft B, the guides *b b*, for the cutting and pressing-die C, the die-box F, which receives the counter-die H, and a block, to which is secured a stationary punch, J.

The counter-die H is hollow, and slides upon the punch J, and is, in the present instance, so acted on by the spring *d* as to be maintained in the position shown in fig. 1, until operated in the manner described hereafter.

Instead of employing the spring *d*, we prefer, in most cases, to impart a positive motion to the counter-die, by any suitable appliances.

The die C, instead of being made hollow for the reception of the end of the punch, as in other machines, is solid, the die, when at the limit of its forward movement, projecting no further into the die-box F than is illustrated in fig. 4.

In using the above machine, the end of the heated bar X, from which the blanks have to be made, is adjusted against a stop, L, secured to the face of the die-box, as shown in fig. 3. The die C then moving forward in the direction of the arrow, cuts off a portion of the bar, and forces the severed piece into the die, and against the counter-die H and end of the punch J.

The die H yields to the extent shown in fig. 4, while the punch J remains stationary; the latter consequently penetrates part way through the blank, and merely indenting the metal, instead of entirely removing a portion of the same.

When the die C is withdrawn, the counter-die H will return to its original position, forcing the indented blank before it, as seen in fig. 5, and this completes the first portion of the process.

The blank thus formed is shown enlarged in fig. 6, *x* representing the indentation formed by the punch J, and *y* the film or web of metal which has yet to be removed.

All that is now necessary to complete the blank, is to remove the same, when cold, or nearly so, to an ordinary punching-machine, the punch *z* of which should have a diameter slightly exceeding that of the indentation *x*.

The partly-finished blank is so adjusted on the machine as to be concentric with the punch *z*, on the descent of which not only is the film or web *y* punched through, but the sides of the indentation are shaved by the sharp cutting-edges of the punch, which thus serves as a reamer, in forming in the blank a clean hole, free from the hard, scaly skin, which, in ordinary forged blanks, tends to impair the cutting-thread of the tap, which must be used for converting the blank into a nut. While the blank thus formed has all the solidity of blanks formed entirely by the combined ac-

tion of heat and pressure, it also possesses the advantage of a cold-punched nut, as regards the hole being in the best condition for the action of the tap.

The web or film y , through which the punch has to cut, is so thin that comparatively little power is required for forcing the punch through the blank; and the duty of the punch is so light that no such disintegration of the metal can take place as must of necessity occur when a punch has to make a hole entirely through the cold metal.

We do not desire to claim, in this application, the mechanism described, as it has been illustrated and described merely with a view of explaining one mode of carrying our process into effect, and not as the only device which could be employed for the purpose.

Claims.

The mode or process, herein described, of form-

ing nut-blanks, that is to say, first indenting the metal while it is hot, and afterward, when the metal is cold, or nearly so, subjecting it to the action of a punch, which completes the hole by removing the indented portion of the metal, and shaving the sides of the indentation, all substantially as set forth.

2. As a new article of manufacture, a nut-blank, formed partly by indenting and pressing the metal when hot, and partly by punching and shaving the same when cold, as herein set forth.

In testimony whereof, we have signed our names to this specification, in the presence of two subscribing witnesses.

JOSHUA W. GASKILL.
JAMES CHRISTIE.
